GOLF CLUB COVER

Reuben J. Banda and Robert H. Storts, Milwaukee, Wis.,
assignors to Hand Knit Products, Inc., Milwaukee,
Wis., a corporation of Wisconsin

Filed Sept. 16, 1960, Ser. No. 62,168

Term of patent 14 years

(Cl. D34—5)

FIG. 1 is a front elevational view of a golf club cover, showing our new design;

FIG. 2 is a side elevational view thereof; and

FIG. 3 is a rear elevational view thereof.

The dominant feature of my design resides in the portion shown in full lines.

We claim:

The ornamental design for a golf club cover, as shown and described.
